CLAIM

The ornamental design for a pharmaceutical package, as shown and described.

DESCRIPTION

FIG. 1 is a front elevational view of a pharmaceutical package showing our new design;

FIG. 2 is a bottom elevational view thereof;

FIG. 3 is a top elevational view thereof;

FIG. 4 is a right side elevational view thereof; and,

FIG. 5 is a left side elevational view thereof.

The undisclosed rear view is planar and unornamented.
